UNITED STATES PATENT OFFICE.

FRANCIS M. A. WYBAILLIE AND LENA WYBAILLIE, OF NEW YORK, N. Y.

SANITARY TOOTH-BRUSH HOLDER.

1,205,311.

Specification of Letters Patent.

Patented Nov. 21, 1916.

Application filed February 25, 1916. Serial No. 80,545.

To all whom it may concern:

Be it known that we, FRANCIS M. A. WYBAILLIE and LENA WYBAILLIE, citizens of the United States, residing at New York, 5 in the county of New York and State of New York, have invented new and useful Improvements in Sanitary Tooth-Brush Holders, of which the following is a specification.

10 The general object of this invention is to refine the construction of tooth brush holders in point of providing a means for conveniently supporting the brushes so that the brush ends may be covered and kept in a 15 clean and sanitary condition and in providing a means for supporting bottles or tubes of dentifrice so that they may be held within convenient reach of a user. And to these ends the invention consists of a bracket 20 on which is arranged a series of devices adapted for supporting the brushes and dentifrice articles and hingedly mounting on the bracket a transparent cover and arranging the same so that when in its closed 25 position the brush ends of the brushes will be covered.

Other objects will appear and be better understood from that embodiment of our invention of which the following is a specification reference being had to the accompanying drawings forming part hereof, in which:—

30 Figure 1 is a perspective view of our improved brush and dentifrice holder showing the same adapted to use. Fig. 2 is a cross sectional view of the same showing the cover swung to an open position in dotted lines. Fig. 3 is a detail perspective view of one of the spring clips detached from the bracket.

35 40 45 1 indicates a bracket comprising a back or wall piece 2 to which is secured a series of spring clamps or clips 3 and 4 indicates a cover hingedly connected to the back or wall piece and arranged for covering a portion of the series of spring clips as shown.

The back 2 is preferably formed of a thin sheet metal and is curved and beveled at its edges as indicated at 5 so as to provide a means for strengthening the same and lending an attractive appearance to the holder. Any suitable means, such as by the screws 6, may be employed for securing the back to a wall or other suitable support. A series of small perforations 7 are formed in the 50 55 back piece adjacent the lower edge thereof and within these perforations are mounted

the clips 3, with which the handles of the brushes are adapted to be engaged for suspendingly supporting the brushes against accidental and unintentional disengagement. 60 The narrow neck portion of the brush handles are preferably designed to be engaged by the spring clips so that the brush ends may be held in substantially an upright position as shown. Large perforations 9 65 are also formed in the back piece, adjacent the side thereof, for receiving the large supporting clips 10, with which the bottles or tubes of dentifrice are engaged for suspendingly supporting the same. The large 70 and small spring clips are similar in structure and each is preferably formed from a single strip of flat metal, bent and curved as shown, to form the clamping jaws 11 75 from the rear ends of which are upstruck the lateral ears 12. These ears are provided for rigidly effecting the engagement of the spring clip with the back piece, the ears being bent against the inner surfaces of the back piece after the clip is inserted within 80 the perforation.

Connected to the back piece by means of the hinges 13 is the cover 4 which is arranged so as to inclose the series of small clips 3 and to cover and protect the brush ends of the brushes when they are held by the clips. The cover is rectangular in cross section and is preferably formed of transparent material such as glass, celluloid or the like so that the various styles of brushes held therein may be seen. By forming the cover of transparent material it will also be obvious that should the holder be placed in a position where it would be struck by the rays from the sun, the sun's rays would penetrate the cover and strike the brushes thereby effectively drying and antiseptically treating the bristles of the same, as is well known. The cover is open at the rear side thereof and has formed on the inner edge of its lower side a series of notches or slots 15, which are arranged in vertical alignment with the brush holding clips and are provided for engagement with the handles of the brushes to permit the cover to effectively close.

In the upper side edges of the cover is formed a series of small air or ventilating holes 16 through which, and through the slots 15, air will circulate thus drying the 110 brushes held within the holder. To more effectively seal the edges of the cover that

contact with the base plate we provide the base plate with a small V-shaped projecting ridge or tongue 16' which fits within a corresponding shaped groove formed in the 5 edges of the cover.

What we claim as new is:—

A brush holder comprising a bracket, clips mounted thereon, a cover hingedly mounted on the bracket at a point above the 10 clips and having notches located at its free edge, the said free edge of the cover being adapted to engage the bracket below the

clips whereby the notches lie vertically under the clips when the cover is in a closed position on the bracket and the clips are incased 15 between the bracket and the cover.

In testimony whereof we affix our signatures in presence of two witnesses.

FRANCIS M. A. WYBAILLIE.
LENA WYBAILLIE.
